UNITED STATES PATENT OFFICE

NELS SWANSON, OF MUSCATINE, IOWA.

FRACTURE-BOX.

1,089,801.

Specification of Letters Patent. Patented Mar. 10, 1914.

Application filed October 20, 1913. Serial No. 796,322.

To all whom it may concern:

Be it known that I, NELS SWANSON, a citizen of the United States, residing at Muscatine, in the county of Muscatine and State of Iowa, have invented certain new and useful Improvements in Fracture-Boxes, of which the following is a specification, reference being had to the accompanying drawings.

This invention relates to new and useful improvements in fracture boxes, the object of the invention being to provide an apparatus of the above character which is especially adapted for use in the treatment of fractures in the lower portion of the leg.

Another object of the invention is the provision of a device of the above character wherein the leg supporting member is adjustable to permit of the leg being raised or lowered, as desired.

A further object of the invention is to provide a fracture box of the above character whereby the same may be readily adjusted longitudinally to adapt the same to legs of various lengths.

A still further object of the invention is the provision of a fracture box of the above character which will possess advantages in points of efficiency and durability, is inexpensive of manufacture and at the same time is simple in construction and operation.

With the above and other objects in view, the invention consists in the novel features of construction and the combination and arrangement of parts to be hereinafter more fully described, pointed out in the claims and shown in the accompanying drawings, in which—

Figure 1 is a side elevation illustrating the manner of use; Fig. 2 is a top plan view; Fig. 3 is a transverse sectional view taken on the line 3—3 of Fig. 2; Fig. 4 is an end elevation, parts thereof being removed; Fig. 5 is a front end elevation; and Fig. 6 is a top plan view, the leg supporting member being removed.

Referring more particularly to the drawings, 1 indicates the base member which is preferably hollow in cross section and slidably mounted upon the bottom thereof is an adjustable member 2 and arranged within the base and secured to the central partition 3 thereof is a rigid member 4, to the outer end of which is hingedly connected the supporting member 5, the upper end of said supporting member being hingedly connected to a second supporting member 6 which

is arranged beneath the box 7 and disposed between the two guide members 8. Mounted upon the supporting member 5 and adapted to move therewith is a bridge plate 9, the purpose of which will be hereinafter more fully set forth.

Hingedly connected to the outer end of the adjustable member 2 is the thigh box 10, the upper end of which is adapted to normally rest upon the bridge plate 9 and may be moved to various adjusted positions and retained in such position by means of the pivoted arms 11 which are pivotally connected, as shown at 12, and having the end portions thereof connected to the base and the box 10. Mounted upon the bridge plate 9 are the side boards 13, which are adapted to be arranged between the extended ends of the thigh box 10. These side plates 13 are connected to and are movable with the bridge plate 9. The extended ends 14 of the fracture box 7 are curved downwardly and provided with the elongated slots 15 in which the headed pins 16 are movable, said pins being carried by the side plates 13 so as to retain a connection between the fracture box and the side plates.

The bridge plate 9 and the fracture box 7 are pivotally connected by means of the links 17, one end of which is pivotally connected to the bridge plate and the other end pivotally connected to the supporting member 6. Mounted upon the base 1 are the spaced bearings 18 in which are mounted the ends of the shaft 19 and mounted upon one end of the shaft is a wheel 20 whereby said shaft may be readily rotated, when desired. Rigidly connected to the shaft 19 at its inner end with an outwardly projecting arm 21, the outer end of which is hingedly connected, as shown at 20 to the supporting member 6 so that upon the rotation of the shaft 19, the fracture box 7 will be raised or lowered as desired.

Mounted upon the end of the shaft opposite the wheel 20 is a collar 23, which is provided with a plurality of openings 24 adapted to receive the downwardly projecting lug 25 which is formed upon the outer end of the pivoted pawl 26 so that when the fracture box has been raised or lowered to the desired position, the lug 25 will engage with one of the openings 24 and retain the shaft 19 against rotation.

At one end of the fracture box 7, an ad-

justable end plate 27 is provided which is hingedly connected to the bottom of the fracture box 7 and is adapted to provide a suitable foot rest to prevent further outward movement of the leg when arranged within the fracture box. The end plate 27 is retained in various adjusted positions by means of the side bars 28, one end of each of said side bars being pivotally connected to the upper end of the plate 27 at each side thereof, while the other end of each of the side bars is provided with a plurality of teeth 29 adapted for engagement with a pin 30 upon each side of the fracture box to retain the end plate in various adjusted positions. The serrated ends of the bars 28 are arranged behind the guide rod 31 so as to prevent any lateral movement of the bars 7 during the operation.

Secured to the outer face of the plate 27 is an angular bracket 32 at the lower end of which is mounted a pulley 33 over which a cord 34 is adapted to pass, one end of said cord extending up and around the foot and is to be suitably padded, as shown at 35, so that the same will not cause any friction with the foot, the other end of said cord extending downwardly over the pulley and having suitable weights 36 secured thereto so that the padded portion 35 will be securely retained in position around the foot so as to securely hold the foot in its proper position. From this it will be seen that after the leg has been placed in position, the padded portion 35 of the cord 34 is adapted to be arranged over the instep of the foot and the weight 36 placed thereon so as to securely hold the foot in position.

In Fig. 1, I have illustrated in dotted lines, a leg in its operative position within the fracture box, the lower portion of the leg being arranged within the box 7 while the upper portion thereof is arranged within the box 10. It will be readily apparent that in placing the leg within the fracture box, the knee should be arranged directly between the two boxes 7 and 10, so that when the shaft 19 is rotated to raise the box 7, there will be no opposition in the bending of the knee.

It will be readily apparent that my device, as illustrated and described, is extremely simple in construction, effective in operation, and can be manufactured and placed upon the market at a very small cost.

It will be apparent that during the adjustment of the fracture box 7, the upper end of the box 10 which is engaged with the bridge plate 9 will be raised or lowered according to the adjustment of the fracture box.

While I have shown and described the preferred form of my invention, it will be obvious that various changes in the details of construction and in the proportions may

be resorted to for successfully carrying my invention into practice without sacrificing any of the novel features of construction or departing from the scope of the appended claims.

What I claim is:—

1. A device of the class described including a base, an adjustable member carried thereby, a rigid member carried by the base, a thigh box pivotally connected to the adjustable member and having pivotal connection with the base, a bridge plate pivotally connected to the rigid member, a fracture box having its free end movably mounted upon the bridge plate whereby the same will be adjusted simultaneously with the fracture box.

2. A device of the class described including a base, a supporting member pivotally connected thereto, a second supporting member pivotally connected to the outer end of the first supporting member, a fracture box carried by said supporting members, a rotatable shaft carried by the base, an arm carried by the shaft and having pivotal connection with the second supporting member, whereby the fracture box may be raised and lowered upon the rotation of the shaft.

3. A device of the class described including a base, a supporting member pivotally connected thereto, a second supporting member pivotally connected to the outer end of the first supporting member, a bridge plate carried by the first supporting member, a fracture box mounted upon the second supporting member, side members carried by the bridge plate, pins extending outwardly from said side boards, the ends of said fracture box having slots to receive said ends, and means for raising and lowering the fracture box, as and for the purpose set forth.

4. A device of the class described including a base, a supporting member pivotally connected thereto, a second supporting member pivotally connected to the outer end of the first supporting member, a fracture box mounted upon the second supporting member, a rotatable shaft mounted upon the base, an arm formed on the shaft and having pivotal connection with the second supporting member whereby rotation of the shaft will adjust the fracture box, a pivoted pawl carried by the base and adapted for engagement with the shaft to prevent rotation of the same.

5. A device of the class described including a base, a supporting member pivotally connected to the base, a second supporting member pivotally connected to the outer end of the first member, a fracture box carried by the second supporting member, a rotatable shaft upon the base, an arm carried by the shaft and having pivotal connection with the second supporting member, a collar carried by the shaft and having a plurality of

openings, a pivoted pawl mounted upon the base and having a lug adapted for engagement within said openings to prevent rotary movement of the shaft, as and for the purpose set forth.

6. A device of the class described including a base, an adjustable member carried thereby, a rigid member also carried by the base, a supporting member pivotally connected to the rigid member, a second supporting member pivotally connected to the outer end of the first supporting member, a fracture box carried by the second supporting member, a bridge plate carried by the first supporting member, a thigh box pivotally connected to the adjustable member and having its free end movably resting upon the bridge plate, and means for adjusting the fracture box with respect to the base, said adjustment simultaneously moving the thigh box, as and for the purpose set forth.

7. A device of the class described including a base, a supporting member pivotally connected thereto, a fracture box, guide members arranged upon the under side of the fracture box and in spaced relation, a

second supporting member movably mounted between said guide members and supporting the fracture box, said supporting member being pivotally connected to the first supporting member, a rotatable shaft mounted upon the base, an arm carried by the shaft and having pivotal connections with the second supporting member, whereby the rotation of the shaft will adjust the fracture box with respect to the base, and means for preventing rotation of the shaft to retain the fracture box in its adjusted position.

8. A device of the class described including a base, supporting member carried by said base, a thigh box having pivotal connection with the base, a fracture box carried by one of the supporting members and a bridge plate carried by the other of said supporting members, as and for the purpose specified.

In testimony whereof I hereunto affix my signature in the presence of two witnesses.

NELS SWANSON.
